SNIPPING MACHINE

Franklin W. Oehrle, Philadelphia, Pa.

Application December 4, 1935, Serial No. 52,763

19 Claims. (Cl. 26—7)

The invention relates to snipping machines for use in the manufacture of tapes or webs of the ladder type, such as are used for supporting the slats of Venetian blinds, and involves certain improvements in elements and in combinations and arrangements thereof for severing interconnecting warp threads or the like between the two body webs in the course of manufacture of tapes of this type.

10 In the manufacture of webs of the ladder type, it is the usual practice to weave the two body tapes and the straps or connecting tapes simultaneously, the connecting tapes being arranged in two parallel rows along the opposite edges of the body tapes. When woven in this manner the two body tapes cannot be separated to form the ladder structure by reason of the cross-over warp threads at the points where the weave for the connecting tapes is transferred from one of the body tapes to the other. In order to permit 15 the separation of the two body tapes, it is the usual practice to sever the cross-over threads of the weave manually by the use of shears. This is a tedious step in the manufacture of such tapes, requiring a number of operators to perform the 20 snipping or severing operation upon the output of a loom.

The primary object of the invention, therefore, is the provision of a machine incorporating a 25 combination and arrangement of elements and suitable actuating mechanism for severing the cross-over threads between two superposed strips or tapes of woven fabric.

Another object of the invention is the provision of an improved cutting device for severing such cross-over threads, and more particularly for severing such interconnecting portions when arranged in staggered relation and at intervals lengthwise of the strips.

40 A further object of the invention is the provision of a suitable stop mechanism for arresting the feed of the superposed interconnected tapes in order that the cross-over threads or other interconnecting portions may be in proper 45 cooperative position with respect to the cutting device.

Still further objects and advantages of the invention will be apparent from the following description, taken with the accompanying drawings, wherein:

Fig. 1 is a plan view of a machine in which the improvements are incorporated;

Fig. 2 is a longitudinal sectional view of the machine taken on the line 2—2 of Fig. 1;

Fig. 3 is a perspective view of a portion of the

machine, showing the feed rolls, the stop mechanism and the cutting device;

Fig. 4 is a plan view of a part of the machine, showing the cutting device in the position which it occupies immediately prior to its inward movement to sever the threads of one of the interconnecting portions along the adjacent edge of the web, with one of the stop fingers in position for arresting the feed of the web;

Fig. 5 is an elevational view taken along the 10 lower edge of Fig. 4, with parts thereof shown in section;

Fig. 6 is a plan view similar to Fig. 4, but showing the cutting device in the position which it occupies immediately prior to its inward movement to sever the threads of one of the interconnecting portions along the far edge of the web, with the other stop finger in position for 15 arresting the feed of the web;

Fig. 7 is a perspective view of a section of 20 ladder web as it comes from the loom, with the cross-over warp threads unsevered; and

Fig. 8 is a perspective view of a section of 25 finished ladder web, with the body tapes separated to receive the slats of a Venetian blind.

The machine in which the various features of the present improvements are incorporated is designed to operate upon an unfinished ladder web 10 made up of two similar parallel tapes or body webs 11, 12 with straps or connecting tapes 13 interwoven therebetween. Such ladder webs are usually made with two spaced rows of connecting tapes 13, one row adjacent each edge of the body tapes. In the process of weaving the ladder web 10, the ends of the straps 13 are 30 interwoven with the body tapes as shown at 14, one end of each strap being interwoven with one of the body tapes and the opposite end of the strap being interwoven with the other body tape. When so woven the cross-over warp threads 15 must be severed before the two body tapes 11 and 12 can be separated to receive the slats of a 35 Venetian blind.

As illustrated in the various figures of the drawings, the interwoven portions 14 in each row 40 are equally spaced, and the interwoven portions provided by one row of straps are so arranged longitudinally of the web as to be midway of the interwoven portions along the opposite edge of the web. When the web is woven in this manner 45 the interwoven portions 14, although arranged in staggered relation, are equally spaced from each other lengthwise of the web.

The various elements of the mechanism utilized in the invention are supported upon a base mem- 50

45

50

55

ber 16 which preferably extends throughout the length of the machine. A table-like support 17 for the web 10 is mounted on a pair of transversely extended brackets 18 secured toward one end of the base member 16. The web 10 may be fed in any suitable manner between a pair of guides 19 on the outer end of the support 17, and is advanced over the support by means of a pair of feed rolls 20, 21 at the end of the support opposite the guides. The lower feed roll 20 is secured on a shaft 22 mounted in a bearing 23 on the base member.

Intermittent rotary motion is provided for the shaft 22 by means of a ratchet wheel 24 fixed thereon and actuated by means of a pawl 25. The pawl 25 is pivoted on a lateral bracket 26 secured to a ratchet arm 27 freely mounted on the shaft 22 adjacent the ratchet wheel 24. A spring-pressed pawl 28 pivotally secured on the bracket arm 29 engages with the toothed wheel 24 to prevent reverse rotation thereof.

The upper feed roll 21 is secured on a shaft 30 mounted in a bearing 31 in the outer end of a swinging arm 32 having its opposite end pivotally secured to the upper end of a bracket 33 on the base member 16. A gear wheel 34 fixed on shaft 30 meshes with a similar gear wheel 35 fixed on shaft 22, so that upper feed roll 21 is positively driven at the same speed as lower feed roll 20. As will be apparent from the manner in which the upper feed roll is mounted, it may be swung upwardly away from the lower feed roll in order that the web may be released for such adjustments of the feed as may be desired.

Intermittent motion is given to the ratchet arm 27 by means of a connecting rod 36 having one end pivotally secured to the free end of the ratchet arm and its opposite end pivoted to a crank arm 37 fixed on the outer end of a stub shaft 38 mounted in a bearing 39 on one end of the base member 16. The stub shaft 38 has fixed thereon a driving pulley 40 to receive a belt 41 by which power is delivered to the machine from any suitable source.

The cutting mechanism which has been designed for severing the cross-over warp threads 15 of the web comprises a shearing device 42 mounted upon a carriage preferably in the form of a reciprocating member 43 movable to and fro in a direction at right angles to the direction of feed of the web on the support 17. The carriage 43 is slidable in a guideway 44 formed in a bracket 45 mounted beneath the support 17 and extending transversely thereof.

The shearing device proper comprises a pair of upper and lower shearing blades 46, 47 pivotally mounted on the upper end of a post 48 secured to and extending upwardly from the carriage 43. Preferably the inner ends of the shearing blades extend slightly over the adjacent edge of the support 17 when the carriage is in its outermost position, and these ends of the shearing blades are spaced from the upper surface of the support such a distance as to freely clear the lower body tape 12 during the reciprocating movements of the carriage and the shears. In order that the upper tape 11 may be separated from the lower one, a pair of spaced separating members 49, 50 is secured along the edge of the support 17 adjacent the cutting device so as to extend inwardly between the edges of the tapes 11 and 12. These separating members are preferably arranged on opposite sides of the shearing device so that the shearing blades 46 and 47 move therebetween during the shearing operation.

The inner edges of the separating members 49, 50 are preferably curved as shown at 51 and 52 in order that the interwoven connections 14 between the straps and the body tapes may be guided about these members and prevent the members from interfering with the feed of the web.

A pair of spaced retaining members 53 is secured along the edge of the support 17 opposite the cutting device 42 for the purpose of retaining the web on the support. These retaining members are preferably of such a shape as to prevent the web from being unduly displaced upwardly from the support and outwardly over the edge thereof, and comprise vertical portions 54 and horizontal overhanging portions 55.

Intermittent reciprocating movement of the carriage 43 is effected by means of an elongated lever 56 pivoted at 57 on a lateral bracket arm 58 on the base member 16, and having one end pivotally secured at 59 to the under-side of the carriage 43. The opposite end of the lever 56 is provided with a cam roller 60 for cooperation with a cam groove 61 in the surface of a suitable barrel cam 62 fixed on a cam shaft 63 mounted in a bearing 64 on the base member 16. The cam shaft 63 is driven by means of a toothed gear wheel 65 fixed thereon and meshing with a toothed gear wheel 66 fixed on the stub shaft 38.

In moving the carriage 43 to and fro in the guideway 44 it is essential that such intermittent action be provided as to move the shearing device 42 into a position to sever the cross-over threads 15 between two interwoven portions 14 along the edge of the web adjacent the shearing device, then move it inwardly into a position to sever the cross-over threads between the next succeeding interwoven portions along the opposite edge of the web, whereupon the shearing device must be retracted in order to be in position to again move inwardly to sever the next succeeding crossover threads 4 along the adjacent edge of the web. These movements may be suitably brought about by forming the cam groove 61 with a dwell *a* to retain the carriage in the position shown in Figs. 1 and 3. Upon further movement of the cam 62 the cam 45 roller 60 enters the inclined portion *b* of the groove to thereby move the carriage inwardly so that the shearing device 42 is in position to sever a group of cross-over threads 15 along the adjacent edge of the web. The cam roller 60 next 50 enters the dwell portion *c* of the groove, during which time the web is advanced by the feeding mechanism so as to bring an interconnecting portion along the opposite edge of the web into cooperative relation with the shearing device as 55 shown in Fig. 6. With the web in this position, the cam roller 60 then enters the inclined portion *d* of the groove to thereupon move the carriage inwardly still further to bring the shearing device into shearing position. The cam roller 60 60 then passes through the dwell portion *e* of the groove and enters the inclined portion *f*, which retracts the carriage to thereby return the shears to the position shown in Figs. 1 and 3.

The shearing blades 46, 47 are actuated by 65 means of a vertical rock shaft 67 supported in the outer end of the carriage 43 and having a cross arm 68 secured on its upper end. One end of the cross arm 68 is connected to the outer end of the shearing blade 46 by means of a short 70 link 69, and the opposite end of the cross arm is connected to the outer end of the other shearing blade 47 by means of a short link 70. With such a connection between the shearing blades it will be apparent that movement of the rock 75

shaft 67 serves to move the operative ends of the shearing blades to and from each other to effect the severing or snipping operation.

The rock shaft 67 is actuated by means of a lever arm 71 secured to the lower end thereof and having pivotally connected to its free end one end of a cam rod 72, the opposite end of which is pivoted to the lower end of a cam lever 73 suspended from a supporting shaft 74 in an overhanging bracket arm 75 mounted on a laterally extending portion 16 of the base member 16. The cam lever 73 carries a cam roller 77 which cooperates with an elongated symmetrical cam groove 78 in the face of a cam plate 79 fixed on the cam shaft 63. With such a cam groove, it will be apparent that the shearing device 42 will be actuated twice during each rotation of the cam shaft 63, these actuations serving to sever the cross-over threads of an interconnecting portion along one edge of the web, and then sever the cross-over threads of the next succeeding interconnected portion along the opposite edge of the web.

While a feed device such as disclosed herein serves to feed the web intermittently to bring the successive interconnecting portions substantially into cooperative position with respect to the severing device, it is essential, in view of the nature of the web upon which the device operates, that positively acting stop means be provided for arresting the feed of the web so that the interconnecting portions will be accurately positioned for cooperation with the severing device. The stop mechanism which has been devised for this purpose comprises a pair of stop fingers 80, 81 alternately actuated to move into and out of position between the tapes 11 and 12 for engagement with the junction of straps 13 with the interwoven portions 14 along the near edge of the web 10. Stop finger 80 is secured to the free end of the long arm 82 of a two-armed lever 83, and finger 81 is preferably secured by adjustable means 84 to the free end of the arm 85 of a three-armed lever 86. The two-armed lever 83 is pivotally mounted on the upper end of a post 87 projecting upwardly from a bracket 88 secured to the under-side of the support 17, and the short arm 89 of this lever is connected by means of a link 90 to the short arm 91 of the three-armed lever 86, which is likewise pivotally supported on the bracket 88.

Pivottally connected to the free end of the arm 92 of the three-armed lever 86 is a cam rod 93 the opposite end of which is pivotally connected to the lower end of a cam lever 94 suspended from the shaft 14. The cam lever 94 carries a cam roller 95 which cooperates with a cam surface on the edge of a cam plate 96 fixed to the cam shaft 63. The roller 95 is maintained in contact with cam 96 by means of a coiled spring 97 having one end secured to the cam lever 94 and its opposite end secured to a bracket arm 98 mounted on the base member 16. The cam plate 96 is of such a shape as to reciprocate the cam rod 93 once during each rotation of cam shaft 63.

It will thus be apparent that, upon each rotation of the cam shaft 63, the stop finger 81 will be moved into and out of position between the two body tapes 11 and 12 on the support 17. It will also be apparent that, by reason of the interconnection between the two-armed lever 83 and the three-armed lever 86, the stop pin 80 will be moved alternately with respect to the stop pin 81 into and out of position between the

two body webs. The arrangement of the stop pins 80 and 81 is such that each pin is brought into position to engage with the successive interwoven connections between each strap 13 along the adjacent edge of the web and the lower body tape 12, and the distance between each pin, in operative position, and the shearing device is such that, when either pin is in engagement with an interconnecting portion, the cross-over threads of the interwoven portions adjacent the shearing device are in proper cooperative position with respect to the shearing device. In view of the equal spacing of the staggered interwoven portions lengthwise of the web, it is sufficient to have the stop pins alternately engage with the interconnecting portions along the adjacent edge of the web, without the necessity of having them engage with the interconnecting portions along the opposite edge of the web.

In order to turn the edge of tape 11 upwardly so that stop fingers 80 and 81 may readily enter between tapes 11 and 12, a tape separating device 99 is secured to bracket 18 near feed roll 20. The separating device 99 is in the form of a rod 25 inclined upwardly to the upper surface of support 17, whereupon it is bent inwardly over the adjacent edge of tape 12, thence upwardly to provide a vertical portion 100 for engagement with the edge of tape 11 to turn this edge upwardly in the manner shown by Figs. 3 to 6 of the drawings.

An elongated retainer 101 is secured to the edge of support 17 opposite the separating device 99 and the stop fingers 80 and 81 for the 35 purpose of preventing undue movement of web 10 away from the support at this point. As in the case of retainer members 53, the retainer 101 is formed with a vertical portion 102 to prevent displacement of the web beyond the edge of the 40 support, and a horizontal portion 103 to prevent undue upward movement.

The feed of the web 10 over the support 17 may be controlled by means of a weight 104. This weight rests upon the web between guide members 19, and it is held against movement with the web by one of the retaining members 53.

Inasmuch as the operation of the various elements of the machine has been described along with the description of the structure of these 50 elements, no detailed description of the operation is believed to be necessary to a complete understanding of the machine. It will be noted, however, that the intermittent feed of the web 10 by the feed rolls 20, 21 is so arranged and timed 55 with respect to the stop mechanism that one or the other of the alternately actuated stop fingers 80, 81 is moved into position between tapes 11, 12 for engagement with an interconnection between a strap 13 and the tape 12 just prior to the completion of an intermittent movement of the web. It will also be noted from Figs. 3 and 4 of the drawings that, when the advance of the web is arrested by stop finger 80, one of the groups of cross-over threads 15 along the near edge of the 60 web is directly in front of the shearing device 42. At this time the carriage 43 is moved inwardly by the portion b of cam groove 61 to position shearing blades 46, 47 on opposite sides of cross-over threads 15. Cam 79 then operates to actuate the shearing blades through cam rod 72, thus severing the adjacent group of threads 15.

The feed mechanism thereupon operates to advance the web to bring the next succeeding group of cross-over threads 15 on the opposite edge of 75

the web into position in front of the shearing device as shown in Fig. 6 of the drawings. In the meantime stop finger 80 has been withdrawn and stop finger 81 is moved into position to engage 5 the interconnection theretofore engaged by finger 80, thereby positively arresting the group of cross-over threads 15 in front of the shearing device. The carriage 43 is thereupon moved inwardly still further by the portion *d* of cam groove 61 to bring the shearing blades 46, 47 on opposite sides of this group of cross-over threads. The shearing blades are again actuated by cam 78 to sever the threads of this group, whereupon portion *f* of cam groove 61 operates to retract the 10 carriage 43 and return the shearing device to the position shown in Figs. 1, 3, and 4 of the drawings. The feed mechanism again operates to bring the next group of threads 15 along the near edge of the web into position in front of the shearing device, whereupon the cycle of operations just referred to is repeated.

While specific forms and arrangements of the various parts of the mechanism have been disclosed, it is to be understood that the disclosure 25 is illustrative only and that changes in form and arrangement of the elements may be made within the scope of the invention as described herein and pointed out in the appended claims.

What I desire to claim as my invention is:

- 30 1. In apparatus for making a ladder web for Venetian blinds, a support for said web, feeding means for advancing said web over said support, a cutting device movably mounted along said support for severing portions of said web arranged at intervals thereon, stop means for arresting the feed of said web when each of said portions is adjacent to said cutting device, and means for actuating said cutting device to sever said portions in succession.
- 40 2. In apparatus for making a ladder web for Venetian blinds, a support for said web, feeding means for advancing said web over said support, a cutting device mounted along said support for severing portions of said web arranged at intervals thereon, stop means for arresting the feed of said web when each of said portions is adjacent to said cutting device, means for moving said cutting device successively into operative position with respect to each of said portions, and 50 means for actuating said cutting device to sever each of said portions in succession.

3. In apparatus for making a ladder web for Venetian blinds, a support for said web, feeding means for advancing said web over said support, a cutting device mounted along said support for severing portions of said web arranged at intervals thereon, stop means intermittently movable into and out of engagement with said web for arresting the feed thereof when each of said portions 55 is adjacent to said cutting device, and means for actuating said cutting device to sever said portions in succession.

4. In apparatus for severing spaced interconnecting portions between two strips of fabric, 65 a support for said strips in superposed position, feeding means for advancing said strips over said support, a cutting device movably mounted along said support, means for separating said strips to permit said cutting device to move freely therebetween, stop means intermittently movable into and out of position between said strips for arresting the feed thereof when each of said portions 70 is adjacent to said cutting device, and means for actuating said cutting device to sever said 75 said interconnecting portions in succession.

5. In apparatus for severing spaced interconnecting portions between two strips of fabric, a support for said strips in superposed position, feeding means for advancing said strips over said support, a cutting device movably mounted along said support, means for separating said strips to permit said cutting device to move freely therebetween, stop means intermittently movable into and out of position between said strips for arresting the feed thereof when each of said portions 10 is adjacent to said cutting device, means for separating the edges of said strips to receive said stop means, and means for actuating said cutting device to sever said interconnecting portions in succession.

6. In apparatus for severing spaced interconnecting portions between two strips of fabric, a support for said strips in superposed position, feeding means for advancing said strips over said support, a cutting device movably mounted along 20 said support, means for separating said strips to permit said cutting device to move freely therebetween, stop means mounted along said support for intermittently arresting the feed of said strips, means for separating the edges of said strips to 25 receive said stop means, and means for actuating said cutting device to sever said interconnecting portions in succession.

7. In mechanism for severing longitudinally spaced, laterally staggered interconnecting portions between two superposed strips of material, a support for said strips, feeding means for advancing said strips longitudinally over said support, a cutting device movably mounted along 30 said support, means for arresting the feed of said strips when each of said interconnecting portions is opposite said cutting device, means for moving said cutting device into position to sever each of said interconnecting portions in succession, and means for actuating said cutting device to 35 sever said interconnecting portions.

8. In a cutting machine, a work support, feeding means for intermittently advancing the work along said support, a cutting device mounted for movement transversely of said support, a cam shaft, a cam on said shaft for moving said cutting device step by step transversely of said support and providing intervening periods of rest, actuating means for said cutting device, a cam on 45 said shaft for operating said actuating means during said periods of rest, stop mechanism mounted along said support for positively arresting the feed of the work during said periods of rest, and a cam on said shaft for actuating said stop mechanism in timed relation with the step by step movements of said cutting device.

9. In apparatus for severing spaced interconnecting portions between two strips of fabric, a support for said strips in superposed position, feeding means for advancing said strips over said support, a cutting device movably mounted along 60 said support, means for separating said strips to permit said cutting device to move freely therebetween, and means for actuating said cutting device to sever said interconnecting portions in succession.

10. In cutting mechanism, a work support, feeding means for advancing the work over said support in a given direction, a carriage mounted along said support for to and fro movement at right angles to the direction of movement of said work, a cutting device secured on said carriage for movement therewith, intermittently actuated means for moving said carriage, means for inter- 70 75 75

mittently arresting the movement of said carriage in one direction, and means for actuating said cutting device when said carriage is in positions of arrested movement.

5 11. In cutting mechanism for operating between two superposed strips of material, a support for said strips, feeding means for advancing said strips over said support in a given direction, a carriage mounted along said support for reciprocatory movement in a direction at right angles to the direction of feed of said strips, a cutting device secured on said carriage for movement therewith, means for separating the edges of said strips adjacent said cutting device to receive said device, means for retaining the edges of said strips opposite said cutting device on said support, means for reciprocating said carriage, and means for actuating said cutting device.

12. In a cutting machine, a work support, feeding means for intermittently advancing the work along said support, a cutting device mounted for movement transversely of said support, a cam shaft, a cam on said shaft for moving said cutting device step by step transversely of said support 25 and providing intervening periods of rest, actuating means for said cutting device, and a cam on said shaft for operating said actuating means during said periods of rest.

13. In work feed arresting mechanism, a support for the work, feeding means for advancing said work over said support, a pair of spaced stop fingers movably mounted along said support, and means for moving each of said fingers alternately into and out of engagement with said work 35 to positively arrest the feed thereof.

14. In work feed arresting mechanism, a support for the work, feeding means for advancing said work over said support, a pair of lever arms pivotally mounted along said support, a stop finger secured on each lever arm, and means for simultaneously actuating said lever arms to move said stop fingers alternately into and out of work feed arresting position.

15. In work feed arresting mechanism, a support for the work, feeding means for advancing said work over said support, a pair of lever arms pivotally mounted along said support, a stop finger secured on each lever arm, intermittently operating means for actuating one of said lever arms to move the stop finger secured thereon into and out of stopping position, and means interconnecting said lever arms to move the stop finger on the second lever arm into and out of stopping position alternately with respect to the stop finger on the first lever arm.

16. In mechanism for intermittently arresting the feed of a pair of superposed strips of material having interconnecting portions spaced lengthwise thereof, a support for said strips, feeding means for advancing said strips over said support, a pair of stop fingers spaced lengthwise along said support for movement into and out of position between said strips, means for separating the edges of said strips to receive said stop fingers, and intermittently operating means for moving said stop fingers alternately into and out of position for engagement with the interconnecting portions of said strips.

17. In a cutting machine, a work support, feeding means for intermittently advancing the work across said support, a cutting device mounted along said support for severing a part of the work, a pair of spaced stop fingers movably mounted along said support, means for moving each of said fingers alternately into and out of engagement with said work to positively arrest the feed thereof, and means to actuate said cutting device simultaneously with the movement of each of said stop fingers into stopping position.

18. In a cutting machine, a work support, feeding means for intermittently advancing the work across said support, a cutting device mounted along said support for severing a part of the work, a pair of lever arms pivotally mounted along said support, a stop finger secured on each lever arm, means for simultaneously actuating said lever arms to move said stop fingers alternately into and out of work feed arresting position, and means to actuate said cutting device simultaneously with the movement of each stop finger into work feed arresting position.

19. In a cutting machine, a work support, feeding means for intermittently advancing the work across said support, a cutting device mounted along said support for severing a part of the work, a pair of lever arms pivotally mounted along said support, a stop finger secured on each lever arm, intermittently operating means for actuating one of said lever arms to move the stop finger secured thereon into and out of stopping position, means interconnecting said lever arms to move the stop finger on the second lever arm into and out of stopping position alternately with respect to the stop finger on the first lever arm, and means to actuate said cutting device simultaneously with the movement of each stop finger into stopping position.

FRANKLIN W. OEHRLIE.

55
